ORIN VANATTA, OF ANAHEIM, AND PAUL VANATTA AND HARRY H. HERN, OF PLACENTIA, CALIFORNIA; SAID HERN ASSIGNOR TO SAID ORIN VANATTA AND SAID PAUL VANATTA

COMBINED ATTACHING AND EQUALIZING DEVICE FOR GUY WIRES

Application filed April 28, 1930. Serial No. 448,154.

This invention relates to a combined attaching and equalizing device for guy wires or cables employed in connection with oil well derricks, standards, uprights, masts, poles or other structures, and the invention has for its object to provide, in a manner as hereinafter set forth, a device of the class referred to for equalizing the pulling and bracing strength of a series of guy wires or cables of different lengths from a single source common to said series of guy wires.

Further objects of the invention are to provide, in a manner as hereinafter set forth, a combined attaching and equalizing device for guy wires arranged in a set or series and which is simple in its construction and arrangement, strong, durable, compact, thoroughly efficient in its use, conveniently operated for equalizing guy wires of the set or series simultaneously, readily assembled, comparatively inexpensive to manufacture, and quickly attached to a single anchoring means therefor.

With the foregoing and other objects in view the invention consists of the novel construction, combination and arrangement of parts as hereinafter more specifically described and illustrated in the accompanying drawings wherein is shown an embodiment of the invention, but it is to be understood that changes, variations and modifications can be resorted to which fall within the scope of the claims hereunto appended.

The drawing illustrates in side elevation the combined attaching and equalizing device showing the adaptation therewith of a series of guy wires of different lengths and with the guy wires connected with a mast.

The device is illustrated, by way of example in connection with a set or series of three guy wires of different lengths in connection with a mast or pole, referred to at 1, but it is to be understood that the device may be employed in connection with a set of guy wires attached to other objects than that as shown, and for which guy wires are employed. The guy wires are arranged in superposed spaced relation and indicated at 2, 3, 4. The wires are connected to spaced eyes 5 which project laterally from the mast 1. An anchoring

post or dead man 6 is arranged adjacent the mast or pole 1.

The device includes a flat, rectangular equalizing bar 7 of the desired length, disposed at a rearward inclination and formed at one end with an opening 8 and at a point between its transverse median and other end with an opening 9. Projecting forwardly from the bar 7, at that end opposite the end provided with the opening 8 is a link 10 which is pivotally connected to the bar 7, as at 11. Arranged forwardly of the bar 7, a substantial distance therefrom is an equalizing lever 12 of materially less length than the bar 7 and disposed at a rearward inclination. The forward end of the link 10 is pivotally connected to the equalizing lever centrally thereof, as at 13. The lever 12 at one end is formed with an opening 14 and at its other end with an opening 15. The lever 12 is so disposed that a portion thereof will be arranged in opposed relation with a part of the bar 7 and the remaining portion thereof will project beyond that end of the bar 7 to which the link 10 is pivotally connected. The inclination of the bar 7 and lever 12 is rearwardly from their lower to their upper ends.

The guy wire 2 is of less length than the wire 3 and has its lower end connected to the lever 12 at the opening 15. The guy wire 3 is of greater length than the wire 2 and has its lower end connected to the lever 12 at the opening 14. The guy wire 4 is of greater length than the wire 3 and its lower end connected to the bar 7 at the opening 8.

Extending through the opening 9 is a ring 16 to which is coupled the forward end of a combined coupling and adjusting element for the guy wires, that is to say, the element provides means for coupling the bar 7 with the anchoring post or dead man 6 and also means for equalizing the pulling and bracing strength of the guy wires. The combined coupling and adjusting element is referred to generally at 17, and includes a threaded hook shaped attaching section 18 loosely connected with the ring 16 and a threaded coupling section 19 having means, or is formed at its outer end, as at 20, for connection to the anchoring post or dead man 100.

6. Adjustably connected with the threaded portions of the sections 18, 19 is a turn buckle 21 for the purpose of adjusting the section 18 relative to the section 19 to provide for simultaneously equalizing the pulling and bracing strength of the guy wires, irrespective of the length of the guy wires with respect to each other.

The device further includes a safety element to maintain it active if a guy wire breaks or becomes detached at either end of the device, as such element functions to prevent the loosening of the other guy wires.

The safety element is disposed diagonally with respect to bar 7 and lever 12 and is secured therewith. The safety element includes a bar 22 disposed diagonally of the lever 12 between pivot 13 and opening 14 and also diagonally of bar 7 between openings 8 and

9. Oppositely disposed U-bolts 23, 24, each carrying a plate 25 and clamping nuts 26 are employed for securing bar 22 to lever 12 and bar 7. The bolt 23 overlaps lever 12 and bar 22 and bolt 24 overlaps bars 7 and 22. The bar 22 is of a length to project from the forward edge of lever 12 and the rear edge of bar 7. The safety element couples bar 7 and lever 12 together.

The ring 16 in connection with the opening 9 provides a pivoting means for bar 7 relative to section 18 of element 17. The manner of setting up the link 10 relative to lever 12 and bar 7 permits of the lever 12 shifting relative to the link 10, the latter relative to bar 7, and the lever 12 and bar relative to each other for the purpose of equalizing the pulling and bracing strengths of the guy wires when element 17 is attached to post 6 and adjusted lengthwise.

It is thought the many advantages of a combined attaching and equalizing device for guy wires, in accordance with this invention, can be readily understood and although the preferred embodiment of the invention is as illustrated and described, yet it is to be understood that changes in the details of construction can be had which fall within the scope of the invention as claimed.

What we claim is:

50. 1. A combined attaching and equalizing device for guy wires comprising an equalizing bar, an equalizing lever of less length than the length of the bar, means extending forwardly from one end of the bar and pivotally connected to said lever centrally of the latter for pivotally suspending it forwardly of the bar and in spaced relation with respect to the latter, said bar and lever having means for receiving the lower ends of a plurality of guy wires, and a lengthwise adjustable coupling element loosely connected at one end to said bar and having its other end provided with means for connecting said element to an anchorage therefor.

65. 2. A combined attaching and equalizing

device for guy wires comprising an equalizing bar, an equalizing lever of less length than the length of the bar, means extending forwardly from one end of the bar and pivotally connected to said lever centrally of the latter for pivotally suspending it forwardly of the bar and in spaced relation with respect to the latter, said bar and lever having means for receiving the lower ends of a plurality of guy wires, and a lengthwise adjustable coupling element loosely connected at one end to said bar and having its other end provided with means for connecting said element to an anchorage therefor, said element connected with said bar between the transverse median of the latter and that end of the bar to which said forwardly extending means is attached.

3. A combined attaching and equalizing device for guy wires comprising an equalizing bar, an equalizing lever of less length than the length of the bar, means extending forwardly from one end of the bar and pivotally connected to said lever centrally of the latter for pivotally suspending it forwardly of the bar and in spaced relation with respect to the latter, said bar and lever having means for receiving the lower ends of a plurality of guy wires, and a lengthwise adjustable coupling element loosely connected at one end to said bar and having its other end provided with means for connecting said element to an anchorage therefor, said element connected with said bar between the transverse median of the latter and that end of the bar to which said forwardly extending means is attached.

4. A combined attaching and equalizing device for guy wires comprising an equalizing bar, an equalizing lever of less length than the length of the bar, means extending forwardly from one end of the bar and pivotally connected to said lever centrally of the latter for pivotally suspending it forwardly of the bar and in spaced relation with respect to the latter, said bar and lever having means for receiving the lower ends of a plurality of guy wires, and a lengthwise adjustable coupling element loosely connected at one end to said bar and having its other end provided with means for connecting said element to an anchorage therefor, said element connected with said bar between the transverse median of the latter and that end of the bar to which said forwardly extending means is attached.

5. A device for the purpose set forth comprising an equalizing bar adapted to have the lower end of a guy wire attached thereto, an equalizing lever adapted to have the lower ends of a plurality of guy wires attached thereto, a link extending forwardly from one end of said bar and having one end pivotally connected to the latter and its other end pivotally connected to said lever centrally there-

of, and a lengthwise adjustable coupling element having its forward end pivotally connected to said bar eccentrically of the latter and adapted to have its rear end anchored.

5 6. A device for the purpose set forth comprising an equalizing bar adapted to have the lower end of a guy wire attached thereto, an equalizing lever adapted to have the lower ends of a plurality of guy wires attached thereto, a link extending forwardly from one 10 end of said bar and having one end pivotally connected to the latter and its other end pivotally connected to said lever centrally thereof, a lengthwise adjustable coupling element 15 having its forward end pivotally connected to said bar eccentrically of the latter and adapted to have its rear end anchored, and a safety element clamped to, disposed diagonally of and secured to said bar and lever.

20 In testimony whereof, we affix our signatures hereto.
